FRAME FOR FURNITURE OR THE LIKE

Clarence L. Dewey, Elkhart, Ind.

Application May 27, 1943, Serial No. 488,646

5 Claims. (Cl. 155—194)

This invention is directed to a frame for metallic furniture or similar structures, supported upon legs which must be rigidly connected with upper sills which afford support for the seat of a chair, stool, couch, or the like, or for a table top or stand with which the legs are associated and to which they must be firmly and rigidly secured in such a way as to avoid the necessity for extraneous bracing.

The invention is primarily directed to furniture construction in which it is desirable to combine beauty of design with rigidity and lightness, so that the resulting structure such as a chair, couch, table or the like will present an attractive and distinctive appearance and so that the mechanical agencies employed in securing the sections together will be concealed from view.

The present invention conforms fully to the above requirements and although for purposes of illustration I shall refer to the structure of a chair, it will be understood that the description is intended to include other articles or structures which may be formed and joined together in a similar manner.

In the drawings:

Figure 1 is a side elevation of a chair embodying the features of the present invention showing an upholstered seat and back in dotted lines;

Fig. 2 is a rear elevation of the same;

Fig. 3 is a sectional plan detail showing the joints between the leg and frame sills;

Fig. 4 is a sectional elevation of the same;

Fig. 5 is a sectional detail showing the method of securing a chair seat to the frame sills;

Fig. 6 is a sectional elevation of one of the frame sills;

Fig. 7 is a composite view showing the inner and outer faces of one of the frame sills and a cross section of the same;

Figs. 8 to 12, inclusive are views illustrating the progressive forms assumed by a section of metallic tubing up to its final completion as a chair leg and back standard; and

Fig. 13 is a plan view showing arcuate sills.

The basic feature of the present invention resides in the formation of the legs and frame or top structure in such a way that the two may be secured together by a firm and rigid union whether the top structure be in the form of a seat frame, table top, or the like and whether the elements which unit with the legs constitute portions of the sills of a frame which carries a seat or the like, or whether they are united with the bottom of a table top or platform.

As shown in the case of a chair, front legs 20

and rear legs 21 are employed, the rear legs being extended upwardly to provide standards 22 for the support of a back 23 conventionally indicated by dotted lines. The front legs as shown extend vertically while the lower portions of the back legs extend obliquely up to the medial vertical section 24 above which the standards 22 extend obliquely backwardly to conform to customary practice. The upper end sections 25 of each of the front legs, and the medial section of each rear leg are of uniform cross section and of maximum dimensions below which in each case the leg is tapered downwardly to a minimum diameter at the foot 26. The cross sectional configuration of each of the legs at the plane of maximum diameter is best illustrated in Fig. 3. It will be noted that the leg in section is of a four-lobed fluted formation affording ridges 27 and intervening grooves 28 which continue throughout the major portion of the leg to a point closely adjacent the foot at which point the grooving terminates in a circular configuration at the foot which rounds inwardly to a flat base 29 as shown in Fig. 12.

The legs stand at the four corners of the chair 25 with their opposed ridges disposed diagonally inwardly and with the adjacent grooves of each leg presenting their divergent walls at right angles to one another, each ridge being formed with parallel side walls 30 and an outer face wall 31 which latter maintains the original curvature of the tubing from which the leg was formed. The adjacent ridge walls diverge at 90°, thus forming a V-shaped groove.

In the case of the chair here shown the rear upper standards taper from the medial section to the tip end 32 which is dome-shaped as shown in Fig. 11. Of course, in the case of a table, stool, stand or the like the upper standards would be omitted.

40 The four legs are connected by straight panelled sills 33 or arcuate sills 33a (Fig. 13) which are united to the legs in the manner shown in Figs. 3 and 4. Each sill is die stamped from a stiff thin plate of metal to provide a channel body 34 which is provided with a longitudinal rib 35 which serves both to stiffen the sill and to provide a panel extending from end to end. The upper and lower edges of the sill are provided 45 with right angularly disposed inwardly extending flanges 36 giving a channel formation to the sill, and the ends of the body and rib are deflected inwardly along a bend at an angle of 45° to present a smooth, oblique face 37, the rim of which is afforded by a narrow lip 38, the ends 39 of the

flanges being clipped to form two end edges making a right angle adjacent the face 37.

Since certain of the ridges protrude diagonally with relation to the sills, the ends of the sills thus formed will fit snugly into the grooves 28 with the flat-faced ends 37, 38 in face contact with the opposed side walls of the ridges 27, and with the clipped ends 39 in close edge contact with the adjacent ridge walls; and in view of the fact that the sill is comparatively wide in a vertical direction, an extended face and edge area of contact is afforded, and the leg will be rigidly socketed between the ends of adjacent sills. An integral union between the sills and the legs is provided by lines of welding 40 which fill into the base of the grooves and along the lips 38 so that an integral bond of fused metal is afforded.

In some cases spot welding or brazing or soldering may be employed, but in all cases the joint will be hidden or concealed from the exterior so that, as viewed from the outside, the union will present the appearance of a close joint or seam along the edge of the ridge with the sill rib standing outwardly therefrom to a slight degree, thereby giving the effect of skillful designing and fine craftsmanship in the joining of the parts while at the same time affording a high degree of strength, rigidity, and durability to the entire structure.

If the frame thus provided is intended to support a chair seat or the like, the same can be fitted and secured in the manner shown in Fig. 5. The seat there shown comprises a rectangular base 41 of plywood or the like the margins of which overlap the upper flanges 36 of the sills to which the base is locked by the heads of screws 42 which overlap the edges of the flanges, and the seat base is covered by a pad 43 or finished in any other suitable manner. If the structure is to serve as a stand or table or the like, in a similar manner, a platform or other form of fitting or appliance may be substituted for the base shown and be secured to the frame sills in any suitable manner.

In order to explain more in detail the nature of the leg formation, reference is had to Figs. 8-12. Fig. 8 shows a section of uniform cylindrical tubing which is first reduced by tapering one or both ends to the form shown in Fig. 9 leaving the middle portion of full diameter. The tapered tube is next drawn through dies or rolls to produce the fluting or grooving shown in Fig. 10.

The bases of the grooves maintain a uniform distance from the axis of the tube at all points while the height of the ridges increases with the distance from the ends of the tube, and remains uniform throughout the medial section of one of the back legs of a chair which would, of course, constitute the upper section of a front leg. In the case of a back leg the tube would be closed at each end as shown in Figs. 11 and 12, while in the case of a front leg the foot end only would be closed as in Fig. 12, while the upper end of full diameter would remain open to afford flush butt contact with the seat base or the like.

Metal legs formed in the manner shown can be produced from an extended length of tubing tapered recurrently to the required extent and afterwards cut into unit sections of the required length and the grooving can be applied to an extended length of recurrently tapered tubing either before or after the same is cut into units. The invention is thus one which enables the

various portions of the chair or other structure to be fabricated by mass production methods and in form to be speedily assembled and united with a minimum of time, effort, and expense. At the same time the resulting article of furniture or the like will present the appearance of fine craftsmanship and may be painted, grained, polished or otherwise finished in such a way which will conform to exacting artistic standards.

10 I claim:

1. In a metallic frame of the character described, the combination of a metallic horizontal sill having an end deflected inwardly to provide a substantially flat attaching face angularly disposed with relation to the vertical plane of the body and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 15 2. In a metallic frame of the character described, the combination of a metallic horizontal sill having a portion of its body offset to stiffen the sill and provide a panel and having an end deflected inwardly to provide a substantially flat attaching face angularly disposed with relation to the vertical plane of the body and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 20 3. In a metallic frame of the character described, the combination of a metallic horizontal sill having a portion of its body offset to stiffen the sill and provide a panel and having an end deflected inwardly to provide a substantially flat attaching face angularly disposed with relation to the vertical plane of the body and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 25 4. In a metallic frame of the character described, the combination of a metallic horizontal sill having a portion of its body offset to stiffen the sill and provide a panel and having an end deflected inwardly to provide a substantially flat attaching face angularly disposed with relation to the vertical plane of the body and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 30 5. In a metallic frame of the character described, the combination of a metallic horizontal sill having a portion of its body offset to stiffen the sill and provide a panel and having an end deflected inwardly to provide a substantially flat attaching face angularly disposed with relation to the vertical plane of the body and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 35 6. In a metallic frame of the character described, the combination of a metallic horizontal sill having a portion of its body offset to stiffen the sill and provide a panel and having an end deflected inwardly to provide a substantially flat attaching face angularly disposed with relation to the vertical plane of the body and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 40 7. In a metallic frame of the character described, the combination of a metallic horizontal sill having a portion of its body offset to stiffen the sill and provide a panel and having an end deflected inwardly to provide a substantially flat attaching face angularly disposed with relation to the vertical plane of the body and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 45 8. In a metallic frame of the character described, the combination of two metallic horizontal sills at an angle to one another each having an end deflected inwardly to provide an attaching face angularly disposed with relation to the vertical plane of the body, and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 50 9. In a metallic frame of the character described, the combination of two metallic horizontal sills at an angle to one another each having an end deflected inwardly to provide an attaching face angularly disposed with relation to the vertical plane of the body, and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 55 10. In a metallic frame of the character described, the combination of two metallic horizontal sills at an angle to one another each having an end deflected inwardly to provide an attaching face angularly disposed with relation to the vertical plane of the body, and a substantially vertical metallic leg having formed therein a longitudinally extending groove affording diverging side walls, at least one of which presents its face in parallel abutting relation to the end face of the sill and in angular relation to the vertical body plane of the sill, and means for uniting said abutting faces together.
- 60 11. In a metallic frame of the character described, the combination of two metallic horizontal sills at an angle to one another each having a portion of its body offset to stiffen the sill and provide a panel and each having an end deflected inwardly to provide an attaching face angularly disposed with relation to the vertical plane of the body, and a substantially vertical metallic leg having formed therein a longitudinally extending groove separated by an intervening ridge, the side walls of which are afforded by the adjacent inner walls of the grooves, the outer groove walls presenting their faces in parallel abutting relation to the end faces of the opposed sills and in angular relation to the vertical body planes of the respective sills, and means for uniting said respective abutting faces together.
- 65 12. In a metallic frame of the character described, the combination of two metallic horizontal sills at an angle to one another each having a portion of its body offset to stiffen the sill and provide a panel and each having an end deflected inwardly to provide an attaching face angularly disposed with relation to the vertical plane of the body, and a substantially vertical metallic leg having formed therein a longitudinally extending groove separated by an intervening ridge, the side walls of which are afforded by the adjacent inner walls of the grooves, the outer groove walls presenting their faces in parallel abutting relation to the end faces of the opposed sills and in angular relation to the vertical body planes of the respective sills, and means for uniting said respective abutting faces together.
- 70 13. In a metallic frame of the character described, the combination of two metallic horizontal sills at an angle to one another each having a portion of its body offset to stiffen the sill and provide a panel and each having an end deflected inwardly to provide an attaching face angularly disposed with relation to the vertical plane of the body, and a substantially vertical metallic leg having formed therein a longitudinally extending groove separated by an intervening ridge, the side walls of which are afforded by the adjacent inner walls of the grooves, the outer groove walls presenting their faces in parallel abutting relation to the end faces of the opposed sills and in angular relation to the vertical body planes of the respective sills, and means for uniting said respective abutting faces together.
- 75 14. In a metallic frame of the character described, the combination of two metallic horizontal sills at an angle to one another each having a portion of its body offset to stiffen the sill and provide a panel and each having an end deflected inwardly to provide an attaching face angularly disposed with relation to the vertical plane of the body, and a substantially vertical metallic leg having formed therein a longitudinally extending groove separated by an intervening ridge, the side walls of which are afforded by the adjacent inner walls of the grooves, the outer groove walls presenting their faces in parallel abutting relation to the end faces of the opposed sills and in angular relation to the vertical body planes of the respective sills, and means for uniting said respective abutting faces together.

angularly disposed with relation to the vertical plane of the body, and a substantially vertical metallic leg having formed therein at least two spaced, longitudinally extending grooves, separated by an intervening ridge, the side walls of which are afforded by the adjacent inner walls of the grooves, the outer groove walls presenting their faces in parallel abutting relation to the end

faces of the opposed sills and in angular relation to the vertical body planes of the respective sills, and means for uniting said respective abutting faces together, said means being in each case in the form of a welding line within the base of the groove and overlapping the end margin of the end face of the associated sill.

CLARENCE L. DEWEY.
